(57) **CLAIM**

The ornamental design for a manually powered food chopper, as shown and described.

DESCRIPTION

FIG. 1 is a perspective view of a manually powered food chopper, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged sectional view of the top plan view of FIG. 7, taken along line 9-9 thereof; and,

FIG. 10 is an enlarged view of a circled portion 10 thereof. The broken line shown are included for the purpose of illustrating portions of the manually powered food chopper which form no part of the claimed design.
